SURFACE ARC ANTECHAMBER SPARK PLUG

Gilbert F. Wright, Renton, and Gaylord W. Newton, Seattle, Wash., assignors to Boeing Airplane Company, Seattle, Wash., a corporation of Delaware

Application August 14, 1951, Serial No. 241,811

19 Claims. (Cl. 123—169)

1

In the present invention surface arcing electrodes are incorporated in spark plug mechanism of the antechamber type. Such spark plug mechanism incorporates an antechamber at the inner end of the plug body, opening through such inner end. Surface arcing type electrodes are mounted at the end of the antechamber remote from its opening.

In surface arc spark plugs the arc is not struck between two point electrodes, but diffuses between two electrodes of substantial area across an intervening surface. In such a spark plug it is an object to maintain the surface across which the arc diffuses free from deposits of carbon and lead compounds.

A more specific object is to accelerate the propagation of combustion in the antechamber of an antechamber spark plug mechanism so as to increase the intensity of the flame projected from the antechamber into the principal combustion space and to reduce the duration of such flame projection so as to expedite the ignition of the entire charge of combustible mixture in the principal combustion space, such as an engine cylinder.

In the design of such a surface arc antechamber spark plug it is a further object to utilize simple construction which will expedite manufacture of the spark plug.

Additional features and advantages of the structures shown as examples in the accompanying drawings are discussed in the following specific description.

Figure 1 is a longitudinal sectional view through one type of spark plug mechanism incorporating the invention, the core being shown in side elevation.

Figure 2 is a fragmentary longitudinal sectional view through a different type of spark plug mechanism with the core shown in side elevation, and Figure 3 is a transverse sectional view of this spark plug taken on line 3—3 of Figure 2.

Figure 4 is a fragmentary longitudinal sectional view through another spark plug modification, a side view of the core being shown, and Figure 5 is a transverse sectional view through the spark plug shown in Figure 4 on line 5—5 of that figure.

Figure 6 is a fragmentary longitudinal sectional view through still a different embodiment of the spark plug with the core in side elevation, and Figure 7 is a transverse sectional view of this spark plug on line 7—7 of Figure 6.

The spark plug shown in Figure 1 includes the metal body 1 in which the insulating core 2, preferably of ceramic material is received. The inner

end of this body is of reduced size and has an external thread 10 adapted to be screwed into the spark plug receiving port of an internal combustion engine. Within this reduced portion is the antechamber cavity 11 which has a mouth 12 opening through the inner end of the spark plug. The shape and size of the antechamber 11 is similar to that shown in Wright application Serial No. 163,155, now Patent No. 2,642,054, except that 10 the core 2 is not spaced from the body 1 over any appreciable distance lengthwise of the spark plug.

In a surface arc type of spark plug the spark does not jump cleanly through an air gap between two electrodes. On the contrary, the area 15 of both electrodes between which the spark travels is rather large, and such electrode areas in each case are adjacent to opposite sides of an intervening surface along which the electricity flows. In such a surface arc type of spark plug 20 considerably lower voltage is required than in the jump spark type of spark plug, although the current utilized is higher. The fouling problem by deposit of carbon or lead compounds from gasoline is very materially reduced because there are 25 no narrow spaces where such foreign substances can accumulate, and moreover, slight deposits of foreign material do not interfere nearly as much with efficient operation of the spark plug.

In the form of spark plug shown in Figure 1 the shoulder 13 at the closed end of the antechamber 11 is integral with the body 1, and on its outer side has a sloping seat for the ceramic core 2. The inner end of the core has an end tapered 30 complementally to such seat, which is pressed against a sealing ring 20 interposed between such core end and its seat. In this relationship, the central electrode 21 extending through the core 2 is disposed at the center of the circle formed by the inner periphery of the shoulder 13.

The shoulder 13 then serves as the grounded electrode for the spark plug so that when a voltage is impressed between the electrode 21 and the body 1 a sheet arc will be struck between the electrode 21 and the shoulder 13 across the space 35 22 of the inner end of core 2. This spark will 40 ignite the combustible mixture in the antechamber 11, projecting an intense tongue of flame through the aperture 12 into the engine's combustion chamber.

The core 2 is held in the position shown in Figure 1 by the securing ring 23 which is pressed against the copper gasket ring 24, preferably of circular cross section, bearing against the core flange 25. The securing ring 23 is held in place 45 after the ceramic core has been seated firmly in

the body cavity by the outer edge 14 of the body 1 being bent inwardly toward the core into overlapping relationship to the ring 23 as shown in Figure 1.

With the exception of the particular arrangement of electrodes and their structure, the cores 2 and bodies 1 of the spark plugs shown in Figures 2, 4 and 6 are the same as the corresponding elements in the spark plug of Figure 1. Consequently, it is not necessary to describe such structure of each of these spark plugs in detail, and the following description is confined principally to the electrode arrangement.

Whereas in the spark plug of Figure 1 the concentric electrodes 21 and 13 were disposed substantially coplanar so that the intervening surface across which the arc is struck by a ring defining a plane disposed transversely of the axis of the spark plug, the central electrode of the spark plug in Figures 2 and 3 is a plate 26 disposed in a plane spaced longitudinally of the spark plug inwardly from the plane of the shoulder 13. The surface 27 across which the arc difuses in a spark plug of this construction is of cylindrical shape, the axis of which is coaxial with the longitudinal axis of the spark plug and is formed by a cylindrical tip on the inner end of the core. The disk 26 is slightly larger than the cross section of this tip so that its peripheral portion forms a circumferential rib or rim constituting one electrode which cooperates with the grounded electrode formed by the shoulder 13. Disk 26 is slightly smaller than the mouth 12 of the antechamber, so that after the core 2 has been assembled with the body 1 in the manner described the conductor 21' for the central electrode disk which it carries may be inserted through the mouth of the antechamber and threaded through the central bore in the core to locate and hold in place the electrode disk 26.

The electrode construction of the spark plug shown in Figures 4 and 5 is generally similar to that of Figure 2 except that in this instance the electrode disk 26' is considerably smaller than the cylindrical portion of the core tip which projects through the aperture within the shoulder 13. Consequently, between the cylindrical portion of the core tip and the electrode disk 26' is a surface across which the arc is struck of truncated conical form tapered from the core tip toward the inner end of the spark plug. The base of this truncated conical portion may lie in the plane of the shoulder 13 at the closed end of the antechamber 11, or if it is desired to locate the surface across which the arc is struck closer to the mouth of the antechamber, a cylindrical collar 13' can be provided extending from the shoulder 13 to the base of the conical portion of the core tip.

Because the disk 26' in this instance is smaller than the cylindrical portion of the core tip and the aperture in shoulder 13 through which it projects, the central electrode can be assembled with the core 2 prior to the inner end of the core being inserted into the spark plug body 1. The same procedure would be followed in fabrication of the spark plug shown in Figure 1.

In Figures 6 and 7 as in Figure 1 the surface 22' across which the arc is struck is disposed in a plane perpendicular to the longitudinal axis of the spark plug. Instead of such surface being annular, however, it is in the form of the base of a groove 22' between the grounded plate electrode 15 and the electrode 28 connected to the conductor 21'. In this construction as in the

spark plug of Figure 2 the tip of the core 2 is cylindrical, but the grounded electrode 15 may actually be carried by the core. Thus this electrode may be formed integral with an arcuate strip 16 embracing a minor arcuate portion of the core tip. The outer end of this strip is integral with a ring 17 having an inclined outer face complementary to an outwardly flaring seat formed on the body shoulder 13'.

The grounded electrode 15 is thus in the shape of a circular segment having its chordal edge spaced from the chordal edge of the electrode 28 which also is planar and shaped as a circular segment. The altitudes of the two segments should be substantially equal; their bases should be parallel and spaced apart to define a groove having a bottom 22' of the width desired across which the arc is to be struck. It will be evident that so long as the adjacent edges of the electrodes 15 and 28 are parallel and these electrodes are coplanar it is immaterial so far as the operation of the spark plug is concerned what their particular shape is, and consequently they may be rectangular, triangular or of other polygonal shape and need not even be of the same shape as long as the adjacent edges are of substantially equal lengths. The segmental shapes of the electrodes 15 and 28 are, however, convenient for the type of assembly illustrated in which these electrodes are assembled on the inner end of the core 2 before it is inserted into the body, and then the ring 17 is pressed into its seat when the inner core end is inserted into the body.

In all the spark plugs discussed it is evident that the surface across which the arc is propagated is located in the antechamber 11 remote from its mouth 12 and in the spark plugs of Figures 1 and 2 is located adjacent to the closed end of the antechamber. The arc will therefore ignite initially the combustible mixture in the antechamber, and as it expands during burning such combustible mixture will eject a tongue of intense flame from the antechamber through its mouth 12 to propagate very rapidly ignition of all the combustible mixture in the engine combustion space into which the antechamber 11 opens.

We claim as our invention:

1. Spark plug mechanism comprising a metal body defining an antechamber of an axial extent approximately equal to its maximum width and having a mouth opening through the inner end of said body of a width approximately half the maximum width of the antechamber, an insulating core having its inner end received in said body, an electrode carried by said core, disposed in said antechamber remote from the mouth thereof and spaced from said body, and an intervening insulating material surface at a location between said electrode and the adjacent portion of said body where such electrode and body are at least as close together as at any other location for diffusion of an arc thereacross between said electrode and said body portion.

2. The spark plug mechanism defined in claim 1, and a plate substantially perpendicular to the axis of the spark plug and carried by the core adjoining such intervening insulating material surface, constituting such core-carried electrode.

3. The spark plug mechanism defined in claim 1, and a shoulder on the body within the antechamber remote from its mouth, adjoining such intervening insulating material surface and constituting the portion of the body adjacent to the electrode between which shoulder and the electrode the arc is diffused.

4. Spark plug mechanism comprising a metal body defining an antechamber having a mouth opening through the inner end of said body of a width approximately half the maximum width of the antechamber, an insulating core having its inner end received in said body, and an electrode carried by said core, disposed in said antechamber remote from the mouth thereof and spaced from said body, the inner end of said core adjoining a portion of said electrode and a portion of said body at least as close together as any other portions of said electrode and body and defining an intervening insulating material surface for diffusion of an arc thereacross between said electrode and said body.

5. Spark plug mechanism comprising a metal body defining an antechamber having a mouth opening through the inner end of said body of a width approximately half the maximum width of the antechamber, an insulating core having its inner end received in said body, an electrode carried by said core, disposed in said antechamber remote from the mouth thereof and spaced from said body, and an intervening insulating material surface disposed in a plane substantially perpendicular to the axis of the spark plug at a location between said electrode and a portion of said body where such electrode and body are at least as close together as at any other location for diffusion of an arc thereacross between said electrode and said body portion.

6. The spark plug mechanism defined in claim 5, and a shoulder on the body within the antechamber adjacent to the intervening insulating material surface and constituting the portion of the body between which portion and the electrode the arc is struck.

7. Spark plug mechanism comprising a metal body defining an antechamber having a mouth opening through the inner end of said body, an insulating core having its inner end received in said body, an electrode carried by said core, disposed in said antechamber remote from the mouth thereof and spaced from said body, and an intervening insulating material surface of substantially cylindrical shape and disposed substantially coaxial with the spark plug axis between said electrode and a portion of said body for diffusion of an arc thereacross between such body portion and said electrode.

8. Spark plug mechanism comprising a metal body defining an antechamber having a mouth opening through the inner end of said body, an insulating core having its inner end received in said body and including a tip portion of insulating material projecting into said antechamber, an electrode carried by said core, disposed in said antechamber remote from and spaced from said body and projecting beyond said insulating core tip, and a shoulder projecting from said body into said antechamber at a location farther from the mouth thereof than the end of said core tip for diffusion of an arc between said electrode and said shoulder across the intervening surface of said core tip.

9. The spark plug mechanism defined in claim 8, and a plate carried by the core tip in a plane substantially perpendicular to the axis of the spark plug, of a width greater than the width of such tip and constituting the electrode.

10. The spark plug mechanism defined in claim 9, in which the core tip includes a portion of cylindrical shape.

11. The spark plug mechanism defined in claim 8, in which the core tip includes an end portion of frustoconical shape.

12. The spark plug mechanism defined in claim 11, and a plate carried by the core tip in a plane substantially perpendicular to the axis of the spark plug, of a width greater than the width of the tip end and constituting the electrode.

13. The spark plug mechanism defined in claim 12, and the shoulder including a collar extending generally axially of the spark plug, encircling the core tip and having its edge closer to the antechamber mouth spaced from the electrode plate for diffusion of an arc across the frustoconical surface of the tip between said collar and the electrode plate.

14. The spark plug mechanism defined in claim 8, a plate carried by the core tip substantially in a plane perpendicular to the axis of the spark plug, constituting the electrode, and a plate substantially coplanar with said electrode plate, spaced edgewise therefrom and grounded to the spark plug body.

15. The spark plug mechanism defined in claim 14, in which the adjacent edges of the plates are parallel over a substantial distance.

16. The spark plug defined in claim 15, in which the parallel edges of the plates are straight and of substantially equal length.

17. The spark plug defined in claim 16, in which the plates are substantially of the same size and shape and are arranged symmetrically about the longitudinal axis of the spark plug.

18. The spark plug defined in claim 17, in which the plates are of circular segmental shape having their bases in spaced parallel relationship.

19. Spark plug mechanism comprising a metal body defining an antechamber having a mouth opening through the inner end of said body of a width approximately half the maximum width of the antechamber, an insulating core having its inner end received in said body, an electrode plate carried by said core and disposed in said antechamber remote from the mouth thereof, a second plate disposed substantially coplanar with said electrode plate, spaced edgewise therefrom and grounded to said body, and an intervening insulating material surface between said two plates for diffusion of an arc thereacross between said plates.
